UNITED STATES PATENT OFFICE.

JOSEPH HIMPEL, OF WEST HAVEN, CONNECTICUT.

UPRIGHT PIANO ACTION.

Application filed March 19, 1923. Serial No. 626,223.

To all whom it may concern:

Be it known that I, JOSEPH HIMPEL, a citizen of the United States, residing at 567 First Avenue, West Haven, in the county of 5 New Haven and State of Connecticut, have invented a new and useful Improvement in an Upright Piano Action, of which the following is a specification.

My invention has reference, in its broad 10 aspect, to improvements in hammer checking devices for upright piano actions, and more particularly it is my purpose to provide means in the form of a check block carried by the hammer-butt for coaction 15 with a lug on the jack of an action unit whereby complete retraction of the hammer of the unit, after it has delivered a blow, is interrupted until the piano key is completely released. Furthermore, I have provided in conjunction with my aforementioned improved hammer check a unique adjusting device for effecting accurate alignment of the hammer with other hammers. 20

Another and equally important object of 25 my invention is to provide a hammer check formed with an uninterrupted curved face for both wiping and positive engagement with a correspondingly curved face of the lug on the jack whereby to facilitate the 30 action of the hammer check; and it is also my purpose to attain by the use of my check the elimination of the usual bridle, bridle wire, back check, back check felts and back 35 check tapes which have heretofore lent to the complexity of piano actions of this type.

The particular elements of my check device employed to accomplish the above and other equally important objects will be hereinafter more fully described in detail and 40 specifically pointed out in the claim appended hereunto and forming a part of this specification.

In the accompanying drawings wherein is 45 illustrated the preferred embodiment of my invention;

Figure 1 is a vertical section of a conventional single action unit showing my device applied thereto, and

Figure 2 is a perspective view of my invention per se.

Like characters of reference refer to like or similar parts throughout the several views of the drawings, in which;

For the purpose of properly disclosing the 55 construction and arrangement of the elements of my hammer check and adjusting

device, I have shown the details of a conventional action unit of an upright piano which consists essentially in frame elements (1), a key (2), and a riser (3) pivotally connected with a jack lever (4) which is carried by the usual action rail (5). Pivoted to the jack lever (5) is a jack (6) formed with a spring pressed heel (7), and limited in movement by the adjustable fixed stop (7a). Also pivoted to the action rail (5) is a hammer-butt (8) carrying the hammer (9), which in its normal inactive position rests upon the hammer rest rail (10) carried by the frame (1). A piano string is shown 70 at (11), and is engaged by the mute (12). Suitable action springs (13) and (14) are provided for an obvious purpose—one operating upon the hammer, and the other upon the mute. All of the above defined structure is conventional and forms no part of my invention.

My invention per se has to do with checking the retraction of the hammer (9) after a blow is struck and before the key (2) is 80 completely released, and in adjusting the alignment of the hammer, with other hammers (not shown). In order to accomplish these ends I have mounted upon the hammer-butt (8) a shaft (15) which extends substantially at right angles to the hammer shaft and carries a head (16) which extends toward and in proximity with the jack (6) and substantially parallel with the hammer shaft. The body portion (17) of the head (16) has a curved uninterrupted 85 face (18) which is adapted to engage a lug (19) formed on the upper end of the jack (6). The lug (19) is provided with a curved, uninterrupted face (20) cooperating 90 with the face (18) whereby to attain a positive as well as a slight wiping engagement therebetween to facilitate the accomplishment of the purposes of my invention. In 95 action, when the hammer (9) is thrown against the string (11) by a blow from the jack (6) the body (17) engages the lug (19) upon the return to interrupt retraction of the hammer until the key is completely released. This permits of the rapid and successive striking of light blows with the hammer as retraction is prevented until the key is completely released, and the hammer maintained at about three-fourths of an inch from the string between blows thereupon. 100 When the key is completely released the hammer moves to a position of rest against 105 110

- the hammer rest rail (10) under the influence of the weight of the hammer, the impulse exerted by the string, and the weight of the check.
- 5 As is clearly illustrated in Figure 2, the head (16) is cut-away as at (21), and seated within said cut-away portion is a block (22), formed with a felted head, and carried by an adjusting screw (23) journaled in the head 10 (16). Thus by turning the screw the block is advanced or retracted within the cutaway portion (21). A perfect alignment of the hammer may be secured by striking the keys, and after the hammers have fallen back into 15 the position assumed before the keys are released, adjusting the blocks (22) so that they raise or lower the hammers into the position desired by engagement with the lug 19 of the jack (6).
- 15 The block (22) serves a double rôle in that it not only makes possible a perfect alignment of the hammers but it insures a perfect catch by the head (16) of the lug 20 (19). If it is so desired the head and lug may be faced with felt or leather as at (24) and (25) respectively; and also the end of the jack and shoulder of the hammer-butt as at (26) and (27).
- I claim;—
- 25 In a check and adjusting device for piano actions, the combination with a hammer, a hammer-butt, and jack of a piano action, of a lug formed on and adjacent to the upper end of the jack and extending outwardly therefrom in an angular direction and provided with a continuously curved uninterrupted face, a check device including a head carried by the hammer-butt and formed with a curved depending body forming a pocket for the lug, and a block adjustably carried by the head and movable to engage the lug in a direction at approximately right angles to the vertical axis of the jack for regulating the position of the hammer.

JOSEPH HIMPEL.
